JOEL BERGLIN, OF NIEDERODERWITZ, GERMANY

RADIO CONTROL DEVICE

Application filed July 11, 1927, Serial No. 204,851, and in Germany July 16, 1926.

The tuning devices already known for measuring and control instruments for the purposes of telegraphy and others requiring some revolutions of the driving device are 5 equipped with several distinct dials, one for one revolution, and with an index hand pointing to the said dials. In these apparatus either the dials are displaced in such a such a manner that always only one dial is 10 opposite to the hand, or the hand is displaced so that it indicates to one of the several dials or a single dial for showing the angle of each half or complete revolution of the driving device and another device for indicating 15 the number of the said half or complete revolutions are provided. But these devices are complicated in construction, doubtful in action and reading and very high in price. For these reasons they have not come into 20 practice.

In consideration of the well known driving gears the device being the object of the present invention is extremely simple, completely proof in action and clear in reading. 25 It allows exact reading at any time without any doubt by using several dials and only one switchable multiple index hand arranged at the tuning part of the device. According to the invention the hand is equipped with 30 various arms, one for each dial, angularly displaced to each other. Furthermore there are one or several projections on the dial in order to switch automatically the index hand from one dial to another.

35 In the accompanying drawing several embodiments of the invention are shown, preferably provided for plate-condensers or the like of broad-casting apparatus.

Fig. 1 is a section along the line I—I of 40 Fig. 2, showing a constructional example, i. e. a device provided with a gear and a switchable three-armed index hand corresponding to three revolutions of the condenser-knob. The section is taken parallel to the panel board of the apparatus and as seen in the direction of the arrows indicated in 45 Fig. 2.

Figs. 2 and 3 are cross-sections along the 50 lines II—II respectively III—III of Fig. 1

as seen in the direction of the arrows indicated at the ends of the section lines.

Figs. 4 and 5 show part views of knobs provided with the hand and catch devices as seen from behind in a direction inclined by about 45° to the axle of the apparatus and on a larger scale than that of the Figs. 1—3. These constructions are provided for only two revolutions of the driving knob over-against a dial consisting of two concentric 60 scales. In these figures the knobs are assumed to be demounted from the journal of the condenser.

In Fig. 6 a three-armed hand for three revolutions of the knob is represented in a 65 view similar to Figures 4 and 5 in an intermediate position when being switched, the knob being only indicated in part.

Fig. 7—corresponding to Fig. 6—is a perspective view of a gear box with holes for 70 the switching of the index-arms and the catch device.

Fig. 8 shows a perspective view of the front part of a condenser in the front board of 75 which a driving gear is elastically mounted.

In the embodiment of the invention shown in Figs. 1 to 3 a plate-condenser 1 of a well known construction is arranged upon the back of a panel board 2, the frustum 3 of its shaft projecting through a suitable bore to 80 the front of said board. A boss 4 of a pinion 5 is secured to the frustum 3 by means of a set screw 6. Over a longer shank 7 of the boss 4 a sleeve 8 having a pinion 9 is rotatably mounted which sleeve 8 is fastened to a 85 normal knob 11 of the condenser by a screw 10.

Furthermore the shank 7 of the sleeve 4 is mounted in a bore of a plate-like holder 12 particularly shaped and arranged between 90 the pinions 5 and 9. In another bore 13 of said holder 12 is journalled a shaft 15 having a pinion 14 at one end and another pinion 16 at the opposite end. The pinion 14 meshes with the pinion 9 and the pinion 16 with the 95 pinion 5 mounted on the frustum 3 by means of the sleeve 4. For securing the gear 14, 16 and the holder 12 against torque an angular stop 17 screwed to the panel board 2 engages a slot 18 of the holder 12. Moreover 100

the holder 12 is provided with a further slot 19 the peculiar shape of which allows a certain resiliency of the part of this said holder bearing, in the bore 13, the shaft 15 and the pinions 14, 16. In consequence of this the 5 pinions 14 and 16 are elastically pressed against the pinions 9 and 5 centrally. A nose 20 of the chief part of the holder 12 may rest against a stop 21 of the part of the holder 12 bearing the pin 15 and may thus prevent this 10 part and stop to yield too much and therefore secures the meshing of the corresponding pinions 5, 16 and 9, 14 respectively.

A dial 34 having three concentric circular scales is arranged upon the panel board 2 15 around the knob 11. At a place on the scales corresponding to the position of maximum and minimum adjustment of the condenser, a stop pin 22 is fixed near the border of the condenser-knob 11.

20 On the back of this border, in a hole 35 of corresponding shape is inserted a metal sheet 36, having a semi-circular hollow 37 opening towards the axle of the knob 11. On the back of the border of the knob, in a line from 25 said axle to said hollow 37, a pin 38 is mounted upon which an index hand 39 having three arms 40, 41 and 42 (see Figs. 1, 2 and 6) is rotatably arranged. At a corresponding distance aside the pin 38, a trunnion 43 is arranged serving as a stop for the end positions of the indicating hand 39, 40, 41 and 42.

Furthermore a catch disk 44 forming a three-pointed star is fastened to the hand 39, 40, 41, 42, adjacent to the back of the condenser-knob. A roller 45 is rotatably mounted on a pin 46 journalled to one end of a plate spring 47 the other end of which is joined to the knob 11 and is resiliently lying against the disk 44.

40 In the embodiments of the invention shown in Figs. 4 and 5 the catch devices differ something from the foresaid construction. The hand 39 according to Fig. 5, on the side opposite to the arms 40, 41 is provided with 45 rounded openings 48 into which a roller 45, elastically secured like that in Figs. 1 and 2, may enter by means of a spring as before-said. According to Fig. 4 the metal sheet 36 is equipped with two lateral laps 49 projecting at a right angle and supporting a plate spring 50 lodged in slots of the said laps. The hand is lying with corresponding stop faces 51 against said spring. In order to secure the 55 guiding of the hand and of the spring a guide part 52 is provided on the back of the index. Moreover in Fig. 4 the stop pin 43 of the first construction (Figs. 1 to 3) is substituted by a border 60 of the groove 35 in the back of the knob.

60 For a supplementary addition of a device according to the invention to a tuning device mounted in an apparatus it is often useful to employ a gearbox consisting of an 65 annular part 56 provided with an end plate

57 as shown in Fig. 7. The annular part possesses corresponding holes 58 and 59 opposite the pin 22 in order to give way for the switching of the index hand and for the catch device. The indicating system and the gear of the latter arrangement are corresponding to those as shown in Figs. 1 to 6; but the pin 38 must be of such a length that the arms of the hand 39 are close to the dial 34. Thus a doubtless, clear and easy reading of the scales is obtained.

70 According to Fig. 8 the gear may be lodged in the front board of the condenser itself. The elastic arrangement of the gear-pinions is attained by a part 55 cut in the shape of a tongue into the board, by milling two slots 54, 75 into the board.

80 The working of the device for controlling the condenser is as follows:

85 The reach of rotation of a normal plate condenser being only 180° ($= \frac{1}{2}$ revolution) is enlarged to several revolutions by means of the gear. Thus a more exact adjustment to the waves of the sending-stations is obtained and the different senders may be separated 90 more easily and more exactly in consequence of the enlarged reach of rotation. In the examples shown in Figs. 1 to 3 and 8 a transmission ratio of 1:3 and one of 1:2 are provided for the gears 5, 16 and 9, 14 equal to a total ratio of 1:6, i. e. to an angle of rotation of 180° of the plates of the condenser 95 correspond to three complete revolutions of the condenser knob 11.

100 Starting on the position of the hand shown in Fig. 1 being assumed to correspond to the minimum adjustment of the hand the arm 40 points to the inner part designated in the figure by scale 34. When rotating the knob 11 and the pinion 9 counter-clockwise (in direction of the arrow indicated in Fig. 1) by means of the gears 9, 14 and 16, 5 the frustum 3 of the condenser is rotated in the same direction. Thereby the sleeves 4 and 8 are rotated relatively to one another. After one 105 revolution of the knob 11 the arm 40, when now being turned further in the same direction pushes against the pin 22, is switched thereby round the pin 38 by an angle of about 120° and then passes the pin 22; the following arm 41 of the hand 39 being longer than the arm 40 is projecting now alone over the border of the knob 11 and points with its extremity to the second (middle) part 110 (marked out by "M") of the scale 34 which part M is now to be used for reading. Together with the hand 39, the catch disk 44 fastened to it is also rotated round the pin 38 by an angle of 120° . The roller 45 slides over the corresponding point of the disk 44 115 into the following recess of the same under the action of the spring 47. Thus the working position of the arm 41 of the hand 39 is exactly adjusted and caught. After the knob 11 has then rotated further on by one 120

125

revolution in the same direction for the second time the hand 39, 40, 41, 42 is switched then again round the pin 38 by means of the pin 22 by an angle of 120° , then the arm 42 projecting alone over the border of the knob 11 is pointing to the outer part (marked out by "O") of the scale 34. Now the arm 41 is resting against the stop pin 43. The catch device 44 is also moved in the foresaid manner during this rotation, whereas during the first rotation of the hand, i. e. when the inner scale is to be used and the arm 40 is projecting over the border of the knob 11, the arm 42 is resting against the pin 43. This pin must be arranged at such a place of the border of the knob 11 that the shortest arm 40 may be turned round the pin 38 without touching the pin 43. When the knob is rotated backwards, i. e. clockwise, the foresaid operations are repeated in a corresponding inverse turn.

In the example according to Figs. 4 and 5 the hand is provided with only two arms 40 and 41 and is only caught in another manner whereas the switching of it is carried out exactly as before-said but only by 90° instead of by 120° the total transmission ratio of the gearing being 1:4 instead of 1:6 in the former case. According to Fig. 4 the arms are caught in their adjustments by the pressing of the spring 50 against the faces 51 of the hand 39.

The construction shown in Fig. 5 has no special catch disk, the hand 39 itself being provided with recesses 48 serving as a catch and into which the roller 45 is pressed by the spring 47.

The construction and working of the embodiment of the invention according to Figs. 7 and 8 are understood from what has been said above having in mind that the gearing has been mounted in the condenser board plate.

The new system of the holder with the gear and the switchable hand for adjustment by many steps may be employed not only for a rotary movement, but also for a straight lined movement, for instance with condensers provided with plates to be shifted endwise instead of being rotated as shown in the drawing. In such case the final pinion of the gear corresponding to the pinion 5 of the figures must co-act with that part of the device to be moved in straight line, e. g. directly for instance by means of a rack or indirectly by means of a drum, an endless rope drive, an endless chain or the like.

Instead of providing the dial with the pin 22 on the board 2 these parts of the device may be arranged on the border of the knob 11; the switchable hand 39, 40, 41, 42 must then be journalled to the panel board. The action and operation is the same as before-said.

I claim:

1. Tuning devices for measuring and control instruments preferably in broadcasting apparatus comprising in combination a transmission gearing the intermediate pinions of which being journaled on a part of the holder of the gearing rendered resilient by indenting a corresponding slot into said holder, said gearing being arranged between the part to be tuned and the driving part thereof which is rotatable by more than one revolution, and an indicating device consisting of a switchable multiple hand and of a multiple dial having a special scale for each revolution and cooperating with said multiple hand. 70

2. Tuning devices for measuring and control instruments preferably in broadcasting apparatus comprising in combination a transmission gearing being arranged between the part to be tuned and the driving part thereof of which is rotatable by more than one revolution, and an indicating device consisting of a switchable multiple hand provided with at least two arms and of a multiple dial provided with a number of scales corresponding to the number of said arms each arm and corresponding scale being provided for only one special revolution of the driving part. 85

3. Tuning devices for measuring and control instruments preferably in broadcasting apparatus comprising in combination a transmission gearing being arranged between the part to be tuned and the driving part thereof which is rotatable by more than one revolution, and an indicating device consisting of a switchable multiple hand provided with at least two arms and of a multiple dial provided with a number of scales corresponding to the number of said arms each arm and corresponding scale being provided for only one special revolution of the driving part. 95

4. Tuning devices for measuring and control instruments preferably in broadcasting apparatus comprising in combination a transmission gearing being arranged between the part to be tuned and the driving part thereof which is rotatable by more than one revolution, and an indicating device consisting of a switchable multiple hand provided with at least two arms and of a multiple dial corresponding to the number of said arms each arm and corresponding scale being provided for only one special revolution of the driving part, switching stops for automatically switching the hand and end stops for terminating the driving movement being arranged cooperating with said switchable hand. 100

5. Tuning devices for measuring and control instruments preferably in broadcasting apparatus comprising in combination a transmission gearing being arranged between the part to be tuned and the driving part thereof which is rotatable by more than one revolution, and an indicating device consisting of a switchable multiple dial provided with at least two arms of different lengths and of a multiple dial provided with a number of scales corresponding to the number of said arms and neighbouring to each other each arm and corresponding scale being provided for only one special revolution of the driving part. 115

In testimony whereof I affix my signature.
JOEL BERGLIN.
